UNITED STATES PATENT OFFICE.

JOSEPH DE HAVEN BUNN, OF YORK, PENNSYLVANIA, ASSIGNOR, BY DIRECT AND MESNE ASSIGNMENTS, TO HENRY S. WIKEL, OF YORK, PENNSYLVANIA.

JACK.

1,064,191.

Specification of Letters Patent. Patented June 10, 1913.

Application filed June 25, 1912. Serial No. 705,694.

To all whom it may concern:

Be it known that I, JOSEPH DE HAVEN BUNN, a citizen of the United States, residing at York, in the county of York and State 5 of Pennsylvania, have invented certain new and useful Improvements in Jacks, of which the following is a specification.

My invention relates to improvements in jacks and more particularly to an improved 10 construction which is designed for elevating automobiles, and other vehicles and which is capable of quick operation by one person to lift the vehicle entirely off the ground.

A further object is to provide an improved jack which is capable of adjustment 15 to receive the front and rear axles of any size of vehicle, and which may be packed in a relatively small space when not in use.

With these and other objects in view, the 20 invention consists in certain novel features of construction and combinations and arrangements of parts as will be more fully hereinafter described and pointed out in the claims.

25 In the accompanying drawings: Figure 1, is a view in elevation illustrating my improvements spread out upon the ground in position to receive a vehicle positioned over the same. Fig. 2, is a view in side elevation 30 showing the vehicle in dotted lines and illustrating the next step in the operation of jacking the machine. Fig. 3, is a broken view in elevation on an enlarged scale showing the jack in its upright position. Fig. 4, 35 is a plan view of Fig. 3. Fig. 5, is a view in elevation of the rear member partly broken away to illustrate the manner of adjusting the uprights. Fig. 6, is a view in longitudinal section through the center of 40 the front member illustrating the manner of adjusting the same. Fig. 7, is a view in section on the line 7--7 of Fig. 6, and Fig. 8, is a perspective view of one of the axle engaging brackets 19.

45 My improved jack comprises a front member 1, and a rear member 2. These members are of general U-shape preferably composed of horizontal and vertical pipe sections 3 and 4 connected by pipe angles 5. 50 The vertical pipe sections 4 constitute the lower members of uprights, the upper members 6 telescoping in the lower members and secured at various adjustments by pins 7

which are projected through openings 8 in lower members 4, and in any of a series of 55 openings 9 in upper members 6.

The pins 7 are connected to the uprights by flexible devices 10 to prevent their loss when the parts are separated. A collar 11 is clamped to the intermediate portion of 60 pipes 3 on front member 1, and a chain 12 is secured to this collar and is adapted to engage a hook 13 on a collar 14 on rear member 2. This chain is of sufficient length to allow of a wide range of adjustment, so 65 that the members may be positioned any desired distance apart by connecting the desired link of the chain with hook 13.

Collars 15 are screwed onto the upper members of the rear uprights, and T-couplings 16 are screwed onto the upper ends 70 of the front uprights. These collars 15 and T-couplings 16 are provided with set screws 17 to clamp the vertical shank portions 18 of angle brackets 19 and 20 respectively. 75 These brackets are constructed to engage the front and rear axles and they project toward each other as seen most clearly in Fig. 3.

The T-couplings 16 on front member 1 80 are connected by pipe 21 which projects through the ends of an arched bar 22. Chains 23 connect the lower portion of the front member 1 with hooks 24 on a bearing bracket 25. This bearing bracket receives a 85 T-coupling 26 into which a pipe 27 is screwed. This pipe 27, at its free end, is of reduced diameter as shown at 28, and internally screw-threaded to receive a tubular screw 29. This tubular screw 29 is externally and internally screw-threaded. Its 90 external screw-threads engage the threads in the restricted end 28 of sleeve 27, while its internal threads which are opposite to the external threads, engage the threads of 95 a screw-threaded rod 30 secured to bar 22.

A toothed wheel 31 is secured to the tubular screw 29 at its free end, and is engaged by a spring-pressed detent or dog 32 carried by a lever 33. The lever 33 has a bearing 34 mounted to turn upon screw 29, and held against longitudinal movement on the screw by means of a collar 35, the latter held in place by a set screw 36. This position of the lever allows it an oscillating movement on the screw 29, and as the spring- 100 105

pressed detent 32 has a beveled lower end, it is free to ride over the teeth of wheel 31 when the lever is swung in one direction, and compel the wheel and screw to turn therewith when moved in the other direction. It will thus be noted that as the tubular screw 29 is turned in one direction, it will cause the screw-threaded rod 30 to move out of the tubular screw 29, and the latter to move out of the pipe 27 to lengthen the prop which consists of bar 22, screw 30, tubular screw 29, sleeve 27 and T-coupling 26.

The spring-pressed detent 32 has rotary mounting in the lever, and is provided with a pin 37 which is adapted to be swung around from side to side and positioned in recessed lugs 38. This movement of the detent allows it to engage the teeth in one direction, and ride over them in the other, and permits the lever to be operated to lengthen and shorten the prop as will be understood.

In operation, the parts are placed in the position shown in Fig. 1. That is, the prop is reduced in length and its T-coupling 26 is outside of bearing bracket 25. The front and rear members 1 and 2 are lying flat upon the ground, and the vehicle 39 illustrated in dotted lines may then be run into position over the jack. The next step is to place the parts in the position shown in Fig. 2, namely, the front and rear members are positioned at an incline with their brackets 19 and 20 engaging the axles of the vehicle and the prop is positioned with its T-coupling 26 in the bearing bracket 25. The chain 12, is of course connected to the hook 13, and when in this position, the operator oscillates lever 33 to lengthen the prop and force the front upright to a vertical position. This movement of the front upright causes the rear upright to assume the same angle, because of the vehicle which acts as a connecting medium between the members, and because the chain 13 prevents any movement of the lower portion of the rear bracket. In other words, the movement of the front bracket imparts a like movement to the rear bracket, and both members may be raised to a vertical position as shown in Fig. 3 to support the vehicle off the ground. When it is desired to lower the vehicle, the detent 32 is reversed and the prop gradually shortened, so as to slowly lower the vehicle onto the ground.

When the device is not in use, the several parts may be disconnected and packed into small space and carried with the vehicle if desired.

Various slight changes might be made in the general form and arrangement of parts described without departing from my invention, and hence I do not limit myself to the precise details set forth, but consider

myself at liberty to make such changes and alterations as fairly fall within the spirit and scope of the appended claims.

Having thus described my invention, what I claim as new and desire to secure by Letters Patent is:

1. A frame consisting of top, bottom and end bars, the ends bars having axle supporting fingers and the bottom bar a hook in combination, and another frame consisting of top, bottom and end bars, the end bars having axle supports and the bottom bar a pin in combination with a chain fastened to the hook and pin. 75

2. The combination of two frames, each 80 consisting of top, bottom and end bars, and having on the end bars clamps and axle supporting fingers held to the end bars by the clamps, and one frame having a hook and the other a pin, with a chain fastened to the hook and pin. 85

3. A frame consisting of top, bottom and end bars, the end bars having axle supporting fingers and the bottom bar a hook in combination, and another frame consisting 90 of top, bottom and end bars, the end bars having axle supports and the bottom bar a pin in combination with a chain fastened to the hook and pin, a jack support, a chain connecting the jack support with the bottom 95 bar of one of said frames, and a jack connected to said last-mentioned frame and adapted to be positioned in the support, substantially as described.

4. The combination of two frames, each 100 consisting of top, bottom and end bars, and having on the end bars clamps and axle supporting fingers held to the end bars by the clamps, and one frame having a hook and the other a pin, with a chain fastened to the hook and pin, a jack support, a chain connecting the jack support with the bottom 105 bar of one of said frames, and a jack connected to said last-mentioned frame and adapted to be positioned in the support, substantially as described. 110

5. A frame consisting of top, bottom and end bars, the end bars having axle supporting fingers and the bottom bar a hook in combination, and another frame consisting 115 of top, bottom and end bars, the end bars having axle supports and the bottom bar a pin in combination with a chain fastened to the hook and pin, a jack support, a chain connecting the jack support with the bottom bar of one of said frames, and a jack 120 connected to said last-mentioned frame and adapted to be positioned in the support, said jack comprising two threaded members movable longitudinally with relation to each other, a ratchet wheel connected to one member, a lever constructed to oscillate on the other of said members, and a dog on the lever constructed to engage the toothed wheel, substantially as described. 125

6. The combination of two frames, each consisting of top, bottom and end bars, and having on the end bars clamps and axle supporting fingers held to the end bars by the 5 clamps, and one frame having a hook and the other a pin, with a chain fastened to the hook and pin, a jack support, a chain connecting the jack support with the bottom bar of one of said frames, and a jack connected to said last-mentioned frame and 10 adapted to be positioned in the support, said jack comprising two threaded members movable longitudinally with relation to each

other, a ratchet wheel connected to one member, a lever constructed to oscillate on 15 the other of said members, and a dog on the lever constructed to engage the toothed wheel, substantially as described.

In testimony whereof I have signed my name to this specification in the presence of 20 two subscribing witnesses.
